GATE LATCH

Andrew C. Thompson and Carl Gill, Madera, Calif., assignors to Thompson & Gill, Inc., Madera, Calif., a corporation of California

Application June 21, 1948, Serial No. 34,206

2 Claims. (Cl. 292—173)

1

This invention is directed to, and it is an object to provide, an improved gate latch for use in connection with ranch gates or the like, where a rugged, heavy-duty latch is required.

Another object of the invention is to provide a gate latch which is readily adjustable to alter the extent of projection of the latch bar; this being desirable not only for initially setting the latch bar for engagement with the catch, but also to compensate for any subsequent varying of the spacing between the free end of the gate and adjacent post on which the catch is mounted.

A further object of the invention is to provide a gate latch which is spring actuated; the spring being enclosed to protect it against damage and frame the weather.

An additional object of the invention is to provide a gate latch which is simple in construction, embodying few parts, and thus being economical to manufacture.

It is also an object of the invention to provide a gate latch which includes a novel arrangement for the reception of a padlock, whereby to secure the latch against opening movement.

A further object of the invention is to provide a practical and reliable gate latch, and yet one which will be exceedingly effective for the purpose for which it is designed.

These objects are accomplished by means of such structure and relative arrangement of parts as will fully appear by a perusal of the following specification and claims.

In the drawings:

Fig. 1 is a side elevation showing the latch as in use on a gate.

Fig. 2 is an enlarged side elevation of the latch, partly in section and detached.

Fig. 3 is an enlarged fragmentary plan view of the inner end of the latch.

Fig. 4 is a cross section on line 4—4 of Fig. 1, showing, in end view, the latch as mounted on a gate.

Referring now more particularly to the characters of reference on the drawings, the improved gate latch comprises an elongated tubular body 1, having a non-circular bore 2 therethrough from end to end. A longitudinal attachment flange 3 is included on the body 1 and extends vertically therefrom adjacent one longitudinal edge.

A latch bar 4 of lesser length than the body 1 is engaged in slidably generally matching relation in the non-circular bore 2 and projects at one end from said bore, as shown. At its inner end the latch bar 4 is formed with a spindle 5

2

which projects through the bore and out of the opposite end thereof; said spindle being threaded at its outer end portion, as at 6.

The outer end of the latch is that from which the latch bar 4 projects, while the inner end of the latch is that from which the threaded portion 6 of the spindle 5 projects.

At its inner end the body 1 is fitted with a cross bar 7 secured in place as by welding; such cross bar 7 including a reduced diameter hole 8 through which the threaded portion 6 of the spindle 5 slidably extends.

A relatively heavy-duty compression spring 9 surrounds the spindle 5 between the inner end of the latch bar and the cross bar 7 at the inner end of the body; such spring 9 being loaded and normally tending to advance the latch bar 4.

Another cross bar 10 is threaded on the projecting portion 6 of the spindle 5 and normally rests in abutment with the cross bar 7; such threaded-on cross bar 10 being fixed, in adjusted position, by a lock nut 11 on the threaded portion 6 of the spindle 5, said nut bearing against the outside of the cross bar 10.

The cross bars 7 and 10 project laterally in the same direction beyond one side of the body 1 as ears 12 having matching holes 13 for the reception of a padlock.

The cross bar 10 also projects laterally in the opposite direction from the body 1 to provide a latch actuating finger 14.

The above described gate latch is mounted and used in the following manner:

The body 1 is seated on the upper edge of one horizontal board 15 of a gate adjacent its free end and between the vertical end boards 16 at said end of the gate.

The outer end of the body 1 is flush with the corresponding end of the gate, and said body is secured in place by cross bolts 17 which extend between the vertical end boards 16 and pass through holes 18 in the attachment flange 3 on said body.

As so mounted in place the rear end portion of the latch is exposed inwardly of the vertical end boards 16 and above the upper edge of the horizontal board 15; the latch actuating finger 14 extending laterally outward with respect to said horizontal board.

A relatively long upstanding hand lever 19 is pivoted at its lower end, as at 20, to the horizontal board 15 on the same side as the finger 14 and directly ahead of the same. From the pivot the hand lever 19 extends upwardly in front of the finger 14 and thence passes, adja-

cent the top of the gate, through a guide strap 21. The hand lever 19 is of such length that it projects above the top of the gate, as shown in Fig. 1.

The hand lever 19 is normally vertical, as in full lines in Fig. 1, at which time the spring 9 holds the latch bar 4 advanced into cooperative engagement with a catch 22 on the gate post 23 adjacent the free end of the gate.

To release the latch the hand lever 19 is swung rearwardly, i. e. in a direction away from the gate post 23. Such motion is transmitted from the hand lever 19 through the engaged finger 14 to the spindle 5, retracting the same along with the latch bar 4. When this occurs, said bar 4 is pulled free of the catch 22 and the gate may be opened.

When it is desired to lock the latch, a padlock is engaged through the matching holes 13 of the laterally projecting ears 12 of the cross bars 7 and 10; this effectively securing said cross bars against separation and consequently preventing opening of the latch.

The normal longitudinal position of the latch bar 4 can be easily adjusted by first loosening the lock nut 11 and then rotating the cross bar 10 on the threaded portion 6 of the spindle 5; the lock nut 11 being reset when the desired adjustment has been effected.

The described gate latch is a very practical, rugged, and reliable device for the intended purpose; the spring 9 being wholly enclosed against damage and also out of the weather.

The design is such that the latch can be readily and easily applied to a gate, and when in use can be manipulated with ease by a person on foot or on horseback.

From the foregoing description it will be readily seen that there has been produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. A gate latch comprising a tubular body, a

latch bar slidable in the body and projecting from one end thereof, the latch bar including a reduced diameter spindle in part in the body and projecting from the opposite end thereof, a pair of cross bars at said opposite end of the body, the inner most cross bar being fixed to the body and the outermost cross bar being secured on the spindle, the innermost cross bar having a reduced-diameter hole through which the spindle slidably projects, a compression spring in the body about the spindle between a shoulder on the latch bar and the innermost cross bar, the outermost cross bar extending laterally of the spindle in one direction as an actuating finger, and a swing lever adapted to be mounted adjacent and crossing the spindle directly ahead of said finger; both cross bars extending laterally in an opposite direction and having communicating holes adapted to receive a locking device.

2. A gate latch comprising an elongated tubular body, a latch bar shorter than the body slidably and non-turnably mounted in and projecting from the outer end of the body, a reduced-diameter spindle on the inner end of the bar projecting from the inner end of the body, a member rigid with and closing said inner end of the body except for an opening through which the spindle slidably projects, the free end portion of the spindle being threaded, a laterally projecting cross bar adjustably threaded and clamped on the spindle and normally bearing against the member to limit the extent of projection of the latch bar from the outer end of the body, and a swing lever adapted to be mounted adjacent and crossing the spindle ahead of the cross bar for engagement with the laterally projecting portion thereof.
